[57] **CLAIM**

The ornamental design of a tooth size and form indicator, as shown.

DESCRIPTION

FIG. 1 is a view of one side of a tooth size and form indicator showing our design.

FIG. 2 is a view of the opposite side thereof.

FIG. 3 is a front view thereof on a larger scale than the preceding figures.

FIG. 4 is a rear view thereof on the same scale as FIG. 3.

FIG. 5 is a top plan view thereof on a still larger scale than FIGS. 3 and 4.

FIG. 6 is a bottom plan view thereof on the same scale as FIG. 5.

FIG. 7 is a sectional view thereof as seen on line 7—7 of FIG. 3 and on the same scale as FIGS. 5 and 6.

FIG. 8 is a sectional view thereof as seen on line 8—8 of FIG. 4 and on the same scale as FIGS. 5—7.
